Primary Examiner — David Muller(74) *Attorney, Agent, or Firm* — Fitch Even Tabin & Flannery LLP(57) **CLAIM**

I claim the ornamental design for a suction handle, as shown and described.

DESCRIPTION

FIG. 1 is a perspective view of an ornamental design for a suction handle;

FIG. 2 is a second perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a rear elevational view thereof; and,

FIG. 8 is a front elevational view thereof.

The broken line showing of parts of the drawings is included for the purpose of illustrating use and environment and forms no part of the claimed design.
